CLAIM

(51) **LOC (15) Cl.** **14-04**

The ornamental design for a display screen or portion thereof with a graphical user interface as shown and described.

(52) **U.S. Cl.**

DESCRIPTION

USPC **D14/485**

1. Display screen or portion thereof with graphical user interface

(58) **Field of Classification Search**

1.1: Front

USPC D14/485-495

1.2: Front

CPC G06F 3/048; G06F 3/0481; G06F 3/0482;

1.3: Front

G06F 3/0485; G06F 3/0487; G06F

3/0482; G06F 3/0483; G06F 3/04842;

G06F 3/04845; G06F 3/04847; G06F

3/0485; G06F 3/04855; G06F 3/0486;

The appearance of the transitional graphical user interface sequentially transitions between the images shown in figs.

1.1-1.3; the process or period in which one image transitions to another image forms no part of the claimed design; for all

(Continued)

figures, the broken lines showing a display screen or portion thereof with graphical user interface form no part of the claimed design; the grayscale tones displayed in the figures are intended to depict tonal contrast, and not any particular shade or tone of color.

1 Claim, 3 Drawing Sheets
